UNITED STATES PATENT OFFICE.

ULYSSES S. HENDERSON, OF COLUMBUS, OHIO, ASSIGNOR TO THE E. M. HULSE COMPANY, OF COLUMBUS, OHIO, A CORPORATION OF OHIO,
SOFA OR DAVENPORT BED.

1,111,457.

Specification of Letters Patent. Patented Sept. 22, 1914.

Application filed April 8, 1914. Serial No. 830,559.

To all whom it may concern:

Be it known that I, ULYSSES S. HENDERSON, a citizen of the United States, residing at Columbus, in the county of Franklin and State of Ohio, have invented a certain new and useful Improvement in Sofa or Davenport Beds, of which the following is a specification.

This invention relates to the type of folding bed shown in the reissued patent of William A. Pease, No. 13,612, dated September 2, 1913.

The objects of the invention are principally twofold, first, to provide means for locking together the members of the outer bed sections and, second to provide means for operating a swinging back to throw it forward and lock it when the bed is folded.

The invention is embodied in the example herein particularly shown and described.

In the accompanying drawing—Figure 1 is a view in elevation of the end of the bed with the end member or standard removed so as to expose the mechanism. In this view the bed is shown as opened. Fig. 2 is a similar view showing the bed closed, much of the mechanism being omitted to avoid confusion and for the sake of clearness. Fig. 3 is a transverse section on the line $x-x$ Fig. 30 1. Fig. 4 is a detail in cross section of a crank on the outer section locking device.

In the views 11 designates the farther one of the two usual end members or main supporting standards in such structures, said members being connected by and supporting the usual stationary frame 10. To the front edge of the frame 10 is hinged at 12^a the seat frame 12.

The characters 13, 14 and 15 designate respectively the regular inner, outer and middle or main sections of the folding bed frame which are operated by suitable devices connected with the seat frame substantially as in the United States patent to Sharp and Pease, No. 1,009,444, dated November 21, 1911 and require no description here because they do not constitute a part of the present invention.

There is also included in the present construction a feature shown in the aforesaid reissued patent of Pease No. 13,612, consisting of a lever 21 pivoted at 22 on a part of the base or frame 10, said lever having at the extremity of its upper arm a lateral inwardly extending bearing 23, said lever also

having connected with its lower end a strong coiled spring 24 that is connected at its rear end to the rear bar of the frame 10 as shown at 25. When the seat frame is closed the edge of the end of that frame depresses the upper arm of the lever 21 and stretches the spring 24 and aids in lifting the seat as set forth in said reissued patent. The present construction also includes a leg 28 in the form of a lever pivoted at 29 to the end of the seat frame and operated by a link bar 30 substantially as set forth in said reissued patent. The present construction also includes added to the bed section 15 a section 31 which is foldingly connected with said section 15 by means of a linking section 32. The folding section 31 has a lever leg 33 (shown in broken lines) pivoted at 34 to the section 31 that is operated by a link 37 to stand at an angle to said bed frame section 31 when the latter is extended as shown and set forth in said patent.

In the present instance the bed frame section 31 is latched to the bed section 15 by means of two latch levers 35 each pivoted at 36 on an end bar of the frame section 31 to swing parallel to said section, said latch lever having a notch 35^a in the end of its longer arm to engage a headed pin 40 (shown in section in Fig. 1.) on the end bar of the section 15. The latch levers 35 are each engaged by crank arms 41 at the ends of a rock shaft 42 journaled in bearings 43 on an angle bar 31^a connected to the end bars of the bed section 31. Also secured to said connecting bar 31^a is a spring 44 the free end of which presses against a crank extension 41^a of the rock shaft 42 and tends to hold the latch levers 35 in engagement with the pins 40 when the frame section 31 is in folded relation with the section 15. The latch levers 35 are released from the pins 40 by pressure with the thumb of the hand on the crank extension 41^a. In closing the section 31 toward the section 15 the latch arms automatically spring onto the pins 40 by reason of the rounded or cammed ends 35^b of the latch levers.

45 designates the back of the davenport, said back being hinged at its upper portion 105 as seen at 46. The lower corners of the back are each provided with a slotted extension 47. Pivoted at 48^a on the frame member 10 is a lever 48 having at its uppermost end a pin 49 engaging the slot of the slotted extension 110

47. The lower end of the lever 48 has a laterally projecting pin 50. The back, when the bed is opened, gravitates to vertical position and throws the lower end of the lever 48 upward. On the lower side of the seat frame is a projecting member 51 that when the seat frame is turned inward to close the bed strikes the pin 50 and throws the lower portion of the back inward as will be apparent by a comparison of Figs. 1 and 2. In fully closing the seat the lower end of the projecting member 51 passes the pin 50 and owing to the relative position of the pivot and the parts forms a lock to prevent any movement of the back, the same being held in the position it is desired it should occupy when the seat is closed.

10 The forms of the parts can be varied without departing from the gist of the invention 20 as claimed.

What I claim is:

1. In a folding bed, the combination with folding bed sections, the outermost of which is provided with a pair of latching arms 25 adapted to engage the contiguous bed section, a rock shaft having cranks to engage said latching arms, and a spring operating

on the rock shaft to hold the latching arms in latching position.

2. In a folding bed, the combination with 30 folding bed sections, the outermost of which is provided with a pair of latching arms adapted to engage the contiguous bed sections, a rock shaft having cranks to engage said latching arms, and a spring operating 35 on the rock shaft to hold the latching arms in latching position, said rock shaft also having a thumb piece for operating the same to cause the release of said latching arms.

3. In a folding bed having an inwardly 40 folding seat, the combination of a swinging back, a slotted extension thereon, a lever engaging at one end said slotted extension, and means on the seat acting directly on the other end of said lever for throwing the lower portion of the back forward, said means also adapted to lock said lever and the back in a position to which it is thrown forward.

ULYSSES S. HENDERSON.
